UNITED STATES PATENT OFFICE.

DAVID SPIVAK, OF NEW HAVEN, CONNECTICUT.

WINDOW-LOCK.

1,346,065.

Specification of Letters Patent.

Patented July 6, 1920.

Application filed October 22, 1919. Serial No. 332,374.

To all whom it may concern:

Be it known that I, DAVID SPIVAK, a citizen of the United States, and a resident of New Haven, in the county of New Haven and State of Connecticut, have invented a new and Improved Window-Lock, of which the following is a full, clear, and exact description.

Among the principal objects which the present invention has in view are the following: To provide a lock of the character mentioned which may be placed in service to provide for window ventilation and secured in such manner as to prevent tampering with the lock; and to provide a lock of the character mentioned, the cost of construction whereof is reduced.

Drawings.

Figure 1 is a perspective view, showing a fragment of two sliding window sashes held against opening movement by a lock constructed and arranged in accordance with the present invention;

Fig. 2 is a face view of said lock shown in its inactive position;

Fig. 3 is a longitudinal section of the same, taken on the line 3—3 of Fig. 2;

Fig. 4 is a face view of the lock when constructed in accordance with the modified form of the invention, the lock being shown in its inactive position; and

Fig. 5 is a longitudinal section of the same, taken on the line 5—5 in Fig. 4.

Description.

As shown in the drawings, a face plate 10 is provided in convenient arrangement with perforations 11, to receive fastening screws 12. The plate 10 has extensions 13 spaced apart to provide a recess 14, to form a runway for the bolt 15.

The bolt 15 is constructed from relatively thin metal and is provided at the one end with a curled portion 16 forming a finger grip for handling the bolt. At the other end the bolt 15 is bent down to form a stop member 17. The stop member 17 and curled portion 16 serve to prevent the withdrawal of the bolt 15 from the channel formed by the overturned edges 18 of the hinge plate 19.

The hinge plate 19 has a curled extension forming a hinge knuckle 20. The metal forming the knuckle 20 is preferably over-

turned upon the hinge pin 21 to form a rigid connection therewith. The ends of the pin 21 are held in the overturned portions of the extensions 13 which form hinge knuckles to coöperate with the pin 21 and 60 knuckle 20.

In the preferred form of the invention, as disclosed in Figs. 1 to 3 inclusive, the bolt 15 is locked in the active position by a screw 22. The screw 22 has a mill head 23 to facilitate the manipulation of the screw. To receive the end of the screw 22, the bolt 15 is provided with an opening 24. When the bolt 15 is actively disposed, as shown in Fig. 1 of the drawings, the opening 24 is in position to receive the end of the screw 22 when the same is manipulated by the person operating the lock. The screw 22 extending thus within the opening 24, the bolt 15 is held rigidly against shifting from the 75 extended position shown in Fig. 1 of the drawings. When the bolt is withdrawn from the active position and disposed in the inactive position as disclosed in Fig. 3 of the drawings, it is found convenient to 80 tighten the screw 22 to prevent the accidental movement of the bolt 15 and plate 19 connected therewith.

Having a lock constructed and arranged as above described, the operation thereof is 85 as follows: The plate 10 is adjusted on one of the stiles of the upper window sash and there secured by the screws 12 with the extensions 13 overhanging the inner edge of the said stile. The pin 21 and curled ends 90 of the extensions 13 are placed so as to avoid interfering with the lower sash of the window when the lock is in the inactive position. When the plate 10 has been thus disposed and it is desired to set the lock in 95 active position, the bolt 15 is moved to a position substantially perpendicular to the plate 10, where the bolt is disposed opposite the recess 14. In this position, pressure is applied to the curled portion 16, 100 the screw 22 having been previously manipulated to disengage the bolt 15, until the opening 24 of the said bolt registers with the screw 22. By manipulating the screw 22 to move the end thereof into the opening 105 24, the bolt 15 is locked in active position. It will be noted that the screw 22 which maintains the bolt in locking position, is inaccessible from below, being disposed above the top rail of the lower sash. The sashes 110

may now be moved to open to the extent permitted by the arrangement of the plate 10 and the bolt 15.

When it is desired to release the lock, this is accomplished by manipulating the screw 22 reversely, withdrawing the bolt 15 until the stop member 17 thereof passes out of the recess 14 in the plate 10, tightening the screw 22 to hold the bolt 15 in the inactive position, when the bolt and hinge plate 19 are swung toward the glass of the upper window sash and out of the path of the lower sash.

In the modified form of the invention, shown in Figs. 4 and 5 of the drawings, a socket 25 is formed on a bracket 26. The socket 25 is provided to receive the one end of and hold the other end of the bolt 15 in position to interfere with and prevent the lifting of the lower sash. The operation of the lock when constructed in accordance with the modified form, is identical with the operation of the preferred form of the lock, except that the screw 22 is dispensed with in the modified construction.

There is also shown in the modified form of the construction eyelets to replace the screw holes in the face plate. When thus constructed several series of screws correctly spaced apart, are placed in the upper sash, and the plate lock is shifted from one series of another, and at will.

Having thus described my invention, what I claim as new, and desire to secure by Letters Patent is:

1. A window lock comprising a face plate adapted to be fixedly mounted on a window stile, said face plate having hinge knuckles extending in service beyond the edge of said stile, said knuckles being spaced apart to form a recess therebetween; a hinge plate pivotally mounted upon said face plate between said knuckles, said hinge plate embodying a slide member, a bolt mounted in said member to pass through said recess to be held thereby in perpendicular relation to said face plate; and a knurled clamp screw provided to clamp the bolt in inwardly disposed or outwardly disposed relation in the slide.

2. A window lock comprising a face plate adapted to be fixedly mounted on a window stile, said face plate having hinge knuckles extending in service beyond the edge of said stile, said knuckles being spaced apart to form a recess therebetween; a hinge plate pivotally mounted upon said face plate between said knuckles, said hinge plate embodying a slide member, a bolt mounted in said member to pass through said recess to be held thereby in perpendicular relation to said face plate; and a knurled clamp screw provided to clamp the bolt in inwardly disposed or outwardly disposed relation in the slide.

3. A window lock comprising a face plate adapted to be fixedly mounted on a window stile, said face plate having hinge knuckles extending in service beyond the edge of said stile, said knuckles being spaced apart to form a recess therebetween; a hinge plate pivotally mounted upon said face plate between said knuckles, said hinge plate embodying a slide member, a bolt mounted in said member to pass through said recess to be held thereby in perpendicular relation to said face plate; and a knurled clamp screw provided to clamp the bolt in inwardly disposed or outwardly disposed relation in the slide, and a socket made integral with the face plate to inclose the end of the bolt to prevent unscrupulous persons from pressing the bolt outwardly.

4. A window locking device for installation upon either one or the other of a double set of windows, comprising a face plate, a guide hinged on the face plate, a bolt slideable in the guide, a screw mounted in the guide to clamp the bolt, and a socket integrally formed with the face plate for covering one end of the bolt to prevent said bolt from being pushed outwardly in the guide.

DAVID SPIVAK.
